UNITED STATES PATENT OFFICE.

OM THORNYCROFT AND JOHN EDWARD THORNYCROFT, OF WESTMINSTER, ENGLAND.

GUN FOR DISCHARGING PROJECTILES BY GASES SUPPLIED THERETO UNDER PRESSURE.

1,340,689.

Specification of Letters Patent. Patented May 18, 1920.

Application filed December 9, 1918. Serial No. 265,920.

all whom it may concern:

Be it known that we, TOM THORNYCROFT and Sir JOHN EDWARD THORNYCROFT, K. B., subjects of the King of Great Britain and Ireland, residing, respectively, at Westminster, England, have invented Improvements in or Relating to Guns for Discharging Projectiles by Gases Supplied Thereto under Pressure, of which the following is a specification.

This invention has for its object to provide a gun or bomb thrower specially adapted for throwing what is known as a depth charge for use in naval warfare, the depth charge comprising a receptacle of cylindrical or other suitable shape charged with high explosive and designed to be thrown to the sea for the destruction of submarine boats.

A depth charge thrower for this purpose, according to the present invention, comprises a short gun barrel, a gas receiver provided with means for generating gases under high pressure by the combustion of cordite or like propellant, such gas receiver being secured lengthwise upon the gun barrel and having its interior connected at its rear end to the rear end of the interior of the gun barrel through short aligned ports or passages of small cross section, means for supporting the gun barrel with associated parts in an inclined position for use, and means for holding a depth charge in position for being thrown from the gun.

The means for generating gases under pressure comprises a combustion chamber (hereinafter called a charge container) made of comparatively small internal capacity and of great strength so as to admit of a large of cordite or like propellant (hereinafter referred to as cordite), being burnt therein under high pressure and comparatively slowly, in order to insure more certain and complete combustion of the whole charge and with less shock than would otherwise be the case. The charge container, provided with suitable firing means, is secured in the gas receiver with which it communicates through a gas exit of comparatively small area and conveniently formed by a number of small apertures in its wall.

A depth charge thrower of the kind referred to can be variously constructed.

In the accompanying illustrative drawings, Figure 1 shows partly in side elevation and partly in central longitudinal section, one construction of depth charge thrower with depth charge, according to the invention. Fig. 2 is a perspective view of these parts. Fig. 3 is a side elevation and Fig. 4 a section on the line A A of Fig. 3, illustrating holding means for a depth charge shown in dotted lines. Fig. 5 is a perspective view showing means for supporting the gun barrel and attached part in position. Fig. 6 is a similar view showing a charge container. Fig. 7 is a perspective view showing a modified construction of the depth charge thrower with depth charge in position and Fig. 8 is a similar view to Fig. 1 but with the depth charge and the means for carrying the same, removed. Figs. 9 and 10 are central longitudinal sections at right angles to one another, showing a firing pistol. The figures are drawn to different scales.

Referring to Figs. 1 to 6 inclusive, *a* is the gun barrel, *b* the gas receiver mounted longitudinally thereon, *c* the charge container, each made of steel, and *d* the firing pistol, the gun barrel and gas receiver being secured firmly together. Formed in the rear end portions of the barrel *a* and gas receiver *b* are a pair of laterally extending adjacent ports or passages *e* and *f* that are adapted, when clamped in alinement with each other, to establish a short direct communication between the interiors of the gas receiver and gun barrel. To insure a gas-tight joint between the rear end portions of the gas receiver and gun barrel, there may, as shown, be inserted at the junction of the ports or passages *E* and *F*, means, such as a double tapered tubular nipple or dowel *g*, that also serves or assists, upon the firing of the gun, to transmit the thrust of recoil from the gun barrel *a* to the gas receiver *b*. As will be seen from Fig. 1, the rear end portion of the gun barrel *a* from which the port or passage *e* extends, forms a gas chamber of less cross sectional area than the remaining or forward portion of the gun barrel. The rear ends of the gun barrel and gas receiver may, as shown, advantageously be secured together by a surrounding metal strap *h* and set screws *i*. The forward end of the gas

receiver *b* is secured to an intermediate portion of the gun barrel *a*, as by two connected rings *j*, *j*¹ that surround the receiver and barrel respectively and are divided diametrically in a vertical plane (see Fig. 5), each pair of half rings being carried by and preferably formed in one piece with an inclined flanged metal plate *j*² fixed to the base plate *k*. The two inclined plates *j*² with half rings *j*, *j*¹ are secured together by through-bolts *m*. In Fig. 2 the divided rings *j*, *j*¹ are carried by a single inclined plate *j*². The gun barrel is provided with a ball end or cascabel *n* secured in a kick socket *o* fixed to the base plate *k*. As will be seen, the construction is such that the various parts of the thrower can be readily made and assembled for use and can be readily taken apart when desired, as for transport.

- 20 20 The means for holding a depth charge in position for being thrown, comprises a ram or plunger *p* (Figs. 3 and 4) adapted to fit the interior of the gun barrel *a* and extending nearly the full length thereof, and a curved plate cradle *r* fixed to the upper outer end of the plunger end adapted, as by the side flanges *r*¹ and end lips *r*², to hold the depth charge *s* in a suitable position for being thrown, conveniently in a horizontal position as shown, in the case of a cylindrical depth charge. The plunger *p* with cradle *r* is prevented from turning in the barrel *a*, as by keys *t* on the plunger fitting into slots *u* in the muzzle end of the barrel *a*, and it can be prevented from accidentally leaving the barrel, during sea stowage, by lashings secured say to rings *v* on the depth charge *s* and to eyes *w* or rings on the sides of the thrower, or it may be, on the deck of the vessel. The plunger *p* may be hard wood and the cradle *r* of steel plates fixed together and secured to the plunger by a through-bolt *x* and nut *y*.

To avoid any possibility of the clearance space in the gun barrel *a* between the lower end thereof and the adjacent end of the plunger *p* being filled with water when at sea, the bottom of the barrel may be provided with a small drain hole *z* (Fig. 1), say of about $\frac{1}{16}$ of an inch in diameter, which is always left open.

The cordite charge used is preferably in the form of a cartridge *c*¹ that fits, or nearly so, the charge container *c*. This container consists (see Figs. 1 and 6) of a perforated cylindrical vessel screwed into the forward end of the gas receiver *b* so as to project into the interior of the gas receiver and having a rounded closed inner end, such container being made of steel having a high yield point, elongation and ultimate strength, and of sufficient thickness to withstand the high gas pressure set up therein on the firing of the cordite charge.

65 For a cordite charge of about four ounces,

which is suitable for throwing a depth charge weighing say about four hundred pounds, to a distance of about one hundred and twenty feet, the charge container *c* may be provided with twenty four holes *c*², each having a diameter of about $\frac{1}{16}$ of an inch so that the gas exit outlet from the container has a total cross sectional area of about 1.85 square inches.

Figs. 7 and 8 show a simplified construction of a depth charge thrower according to the invention. In this case the gun barrel *a* with its support *j*³ for holding it in an inclined position, say about 50°, and its base plate *k*, are made of cast iron, in one piece, cast iron of good quality being sufficiently strong to withstand the comparatively low pressures employed in the barrel, say about six hundred pounds to the square inch, without having to make the barrel unduly thick. For use, the base plate *k* may be secured, as by bolts, to a steel base plate secured to the deck of a vessel or other structure upon which it is to be used. The gas receiver *b* is secured to the barrel by metal straps *h*¹ and *h*² each of which is secured, as by set screws *i*¹, *i*² to lugs *a*¹, *a*² cast in one piece with the barrel, the straps embracing the gas receiver *b* at the end portions thereof and being held in position thereon, as by screws *i*³. In this example, both the cradle *r* and the plunger *p* for carrying it are made of steel plate, the plunger being hollow. In other respects this modified but simplified construction of depth charge thrower is substantially similar to that shown in Figs. 1 and 2.

The firing pistol shown at *d* in Figs. 1 and 2 may be constructed in various forms. It may however advantageously be constructed as shown more clearly in Figs. 10 and 11. In this example it comprises a tubular body 1 adapted to be readily screwed into and removed from the outer end of the cordite container *c* and provided with a hammer 2 and spring 3 of the rebounding lock type, which is normally uncocked and is adapted to be fired by a pull-through wedge 4 which can be operated by hand or by a lanyard. A locked safety bolt 5 passed across the top or outer end 2^a of the hammer 2 and through an open guard 6 secured to the tubular body 1, serves to prevent the firing wedge 4 being withdrawn until it has been unlocked and removed. The inner end of the pistol body is adapted, as by providing it with a lip 7, or there may be more than one, to fit the rim on the cordite cartridge and support the cartridge in position within the cordite container, and also to act as the extractor for the cartridge case. An indicator, such as a spring pin 8, may be provided on the side of the pistol body to show when a cartridge is in the charge container. When a cartridge

in position, the spring pin 8 is held in its ter position by the cartridge against ich it bears.

The operation of the apparatus is as fol-
vs:

cordite charge or cartridge c^1 being placed the container c the firing gear d is placed position ready to be actuated. When it desired to throw a depth charge s from the barrel a , the firing gear is operated in usual way, as through a lanyard or other vice, and the charge or cartridge c^1 ignited, as the resulting gases are restricted in lume owing to the construction of the arge container c used, the cordite burns mpletely under high pressure. The result-
g gases pass into and are collected in the eiver b and thence pass through the holes nd f into the breech end of the gun. As the dite is burnt under pressure and com-
atively slowly, there will be very little ock due to its combustion and the result-
g gases will pass from the gas receiver into
e gun barrel through the holes e and f in
steady and continuous manner without
lent shock, and with a comparatively low
d steady pressure, so that they will act in
advantageously manner upon the plunger
and throw it and the cradle r and depth
arge s away from the gun barrel in a defi-
te and effective manner.

By means of depth charge throwers con-
ucted and operating as described, a depth
arge, the casing of which is made com-
paratively thin, can be readily thrown for-
ard without any liability of its being pre-
aturely exploded by the set back, due to
inertia, at the instant of projecting it
om the gun barrel. Also, as it is thrown
ward by gas under pressure produced by
mbustion of a propellant in a chamber
parate from the gun barrel, and connected
reto through a passage of small cross sec-
onal area, there is no danger of flame, due
combustion of the propellant, coming into
ntact with the depth charge.

What we claim is:—

1. A gun adapted to throw a depth charge, mprising a gun barrel, a gas receiver con-
cted at its rear end to the rear end of said
barrel by a connecting passage of less
oss sectional area than said receiver and
id gun barrel, a charge container having a
stricted outlet in communication with said
receiver so that a combustible charge in
id container can be burnt under high pres-
re to generate gases under high pressure
d admit such gases to the gas receiver at
duced pressure and to the gun barrel at
still lower pressure, means for support-
g the gun barrel in position for use, a
unger fitting the bore of the gun barrel
d free to be thrown out of and away from
e gun barrel by gases under pressure ad-
ited to the rear end of the gun barrel and

means carried by the outer projecting end
of the plunger adapted to support a depth
charge in position to be thrown.

2. A gun or depth charge thrower, comprising a gun barrel, means for supporting the same in an inclined position for use, a gas receiver connected to the rear end of said gun barrel through a passage of restricted cross sectional area, a charge container extending into and carried by said gas receiver and adapted to admit of a charge of propellant being readily inserted therein, said charge container having a gas outlet of restricted cross sectional area for the purpose set forth, means for firing said charge of propellant for producing gases under high pressure, a plunger fitting the bore of the gun barrel and free to be thrown out of and away from said gun barrel by gases under pressure admitted to the rear end of said barrel and means carried by said plunger for supporting a depth charge outside of said gun barrel.

3. A gun or depth charge thrower, comprising a gun barrel, means for supporting the same in an inclined position for use, a gas receiver mounted on said gun barrel and in direct communication with the rear end thereof through a passage of restricted cross sectional area, a charge container lo-
cated within and secured to said gas receiver and in communication therewith through a gas outlet of restricted cross section, means for firing a charge of propellant in said charge container and a plunger fitting the bore of said gun barrel and free to be thrown out of and away from said gun barrel, the outer end of the plunger being adapted to hold and support a depth charge outside of the gun barrel.

4. A gun or depth charge thrower accord-
ing to claim 1, wherein the gas receiver with
charge container is detachably connected to
the gun barrel.

5. A gun or depth charge thrower accord-
ing to claim 1, wherein the gas receiver with
means for producing gases under pressure is
secured lengthwise upon the gun barrel and
has its rear end in direct communication
with the rear end of the gun barrel through
aligned ports or passages.

6. A gun or depth charge thrower accord-
ing to claim 1, wherein the plunger is a non-rotatable one and the means for sup-
porting a depth charge is in the form of a holder extending across and at right angles
to the plunger.

7. A gun or depth charge thrower accord-
ing to claim 1, wherein the outer end of the gun barrel and an adjacent part of the plunger are provided with interengag-
ing parts to prevent rotation of the plunger.

8. A gun or depth charge thrower accord-
ing to claim 1, wherein the means car-
ried by the outer end of the plunger for

supporting a depth charge of cylindrical shape, consists of a part cylindrical holder having lateral lugs at its ends adapted to retain a depth charge laterally in place in 5 said holder.

9. A gun or depth charge thrower according to claim 2, wherein the charge container is provided with a firing pistol comprising a tubular body that is adapted 10 to be detachably connected to the charge container and is provided with a hammer and spring of the rebounding lock type adapted to be fired by a pull-through wedge and with a guard adapted to hold and support a locked safety bolt across the outer end of the hammer.

10. A gun or depth charge thrower having a firing pistol according to claim 9, wherein the inner end of the body of the 20 pistol is adapted to hold the rim of a cordite cartridge and support the cartridge within the charge container and also to act as an extractor for the cartridge case.

11. A gun or depth charge thrower having a firing pistol according to claim 9, wherein the body of the pistol is provided with an indicator adapted to show when a cartridge is in the cordite container.

12. A gun or depth charge thrower comprising a gun barrel, a base therefor, means for supporting said gun barrel in an inclined position on said base, a plunger fitting said barrel and provided at its outer end with a cradle for supporting a depth 35 charge, a gas receiver mounted upon and detachably clamped to said gun barrel and having its rear end in direct connection with said gun barrel, through a passage of reduced cross section, a charge container secured within the forward end of said gas receiver and in communication therewith through a restricted gas outlet, and a firing pistol for firing a charge within said charge 40 container.

13. A gun or depth charge thrower comprising a base, a gun barrel integral therewith and supported thereby in an inclined position a plunger fitting said barrel and provided at its outer end with a cradle for 45 supporting a depth charge, a gas receiver detachably mounted upon said gun barrel and having its rear end in direct communication with the rear end of said gun barrel, a charge container within the forward end 50 of said gas receiver and in communication therewith and a pistol for firing a charge within said charge container.

14. A gun or depth charge thrower according to claim 13, wherein the forward 60 end of the gun barrel is provided with notches and the combined plunger and carrier with lugs adapted to enter said notches for the purpose set forth.

15. A gun or depth charge thrower com-

prising a gun barrel, a plunger freely fitting said gun barrel and provided at its outer end with a cradle adapted to support a depth charge, a separate longitudinally arranged tubular gas receiver carried by said gun barrel and having its rear end in direct and free communication with the rear end of the gun barrel through a short passage of restricted cross sectional area, means for securing said gas receiver to said gun barrel, a perforated tubular charge container extending into and carried by the gas receiver, the perforations in said charge container forming a gas outlet of restricted cross sectional area, substantially as described for the purpose set forth, between said charge container and gas receiver, firing means for igniting a charge of propellant within said charge container, and means for supporting said gun in position for use.

16. A gun or depth charge thrower, comprising a gun barrel, a plunger freely fitting said gun barrel and provided at its outer end with a cradle adapted to support a depth charge, a separate gas receiver arranged longitudinally upon and carried by said gun barrel, a perforated tubular charge container extending into and carried by said gas receiver, firing means carried by said charge container, said gun barrel having at its rear end a gas chamber of less cross sectional area than the portion of the barrel in which the plunger is fitted, and having a short lateral passage extending therefrom, and said gas receiver having at its rear end a lateral passage in alinement with the lateral passage extending from said gas chamber, said lateral passages being each of less cross sectional area than said gas chamber and gas receiver and means for connecting the gas receiver to the gun barrel in a detachable manner.

17. A gun or depth charge thrower comprising a gun barrel, a plunger fitting said barrel and provided at its outer end with a cradle for supporting a depth charge, a separate gas receiver arranged longitudinally upon and carried by said gun barrel, a perforated tubular charge container extending into and carried by said gas receiver, firing means carried by said charge container, said gun barrel having at its rear end a gas chamber of less cross sectional area than the portion of the barrel in which the plunger is fitted and having a short lateral passage extending therefrom and said gas receiver having at its rear end a lateral passage in alinement with the lateral passage of said gas chamber, said lateral passages being each of less cross sectional area than said gas chamber and gas receiver, means for connecting the forward end of the gas receiver to the gun barrel in a detachable manner and means

for clamping the rear end of the gas receiver to the rear end of the gun tube in a detachable manner.

18. A gun or depth charge thrower comprising a gun barrel, a base plate and supporting plate integral with one another, with the barrel inclined to the horizontal, a plunger fitting said gun barrel and provided at its outer end with a cradle adapted to support a depth charge in position to be thrown, a gas receiver arranged longitudinally upon said gun barrel, detachable straps securing said gas receiver to said gun barrel, the rear ends of said gun barrel and gas receiver being in communication 15 with one another through a short connecting passage of less cross sectional area than that of the gun barrel or gas receiver, a perforated charge container located within and carried by said gas receiver, and firing means at the forward end of said gas receiver for firing a combustible charge of propellant within said charge container. 20
- 10 to support a depth charge in position to be thrown, a gas receiver arranged longitudinally upon said gun barrel, detachable straps securing said gas receiver to said gun barrel, the rear ends of said gun barrel

Signed at London, England, this thirteenth day of November, 1918.
